ADJUSTABLE PISTON FOR GAS ENGINES

Ralph F. White, San Bernardino, Calif.

Application December 2, 1943, Serial No. 512,623

3 Claims. (Cl. 309—12)

The invention relates to engine pistons, and more especially to adjustable pistons for engine cylinders.

The primary object of the invention is the provision of a piston of this character, wherein the cross-sectional diameter can be regulated, without impairing the proper fitting of its head and connecting rod pin, the piston being of novel construction, and is unique in its make-up, it having a split interlocking characteristic, insuring maximum life and service.

Another object of the invention is the provision of a piston of this character, wherein slack in the same due to wear can be readily and easily taken-up to assure proper compression within the cylinder having it fitted therein, with an increase in power and a saving in gas and oil.

A further object of the invention is the provision of a piston of this character, wherein through adjustment thereof, the re-boring of cylinders is obviated, and an adjustment can be made without removing the piston from its cylinder of the engine in which it is installed.

A still further object of the invention is the provision of a piston of this character, which is simple in construction, thoroughly reliable and efficient in purpose, strong, durable, readily and easily adjusted, thereby saving repair costs, and inexpensive to manufacture and install.

With these and other objects in view the invention consists in the features of construction, combination and arrangement of parts as will be hereinafter more fully described, illustrated in the accompanying drawing, which shows the preferred embodiment of the invention, and pointed out in the claims hereunto appended.

In the accompanying drawing:

Figure 1 is a sectional view taken on the line 1—1 of Figure 2 looking in the direction of the arrows, showing the piston constructed in accordance with the invention.

Figure 2 is an elevation of the piston.

Figure 3 is a top plan view of the same.

Figure 4 is a sectional view taken transversely of the piston on the line 4—4 of Fig. 1.

Figure 5 is a fragmentary perspective view, partly broken away.

Similar reference characters indicate corresponding parts throughout the several views in the drawing.

Referring to the drawing in detail, A designates generally a piston constituting the present invention for use in an engine cylinder, and comprises a sectional cylindrical body forming a skirt to the piston, involving the companion sections

10 and 11, respectively, which are halves of the said body and match each other in the assembly of the latter.

These sections 10 and 11 at their meeting edges longitudinally thereof have straight rabbeted lower edge portions 12, and upper rabbeted saw tooth-like remaining edge portions 13, throughout, the latter edge portions 13 being extended beyond the edge portions 12 and intermesh with 10 each other.

The compression end of the body of the piston A has removably fitted therein a disk-like closure head 14, which is formed with a beveled screw threaded peripheral edge 15, adjustably engaging 5 a companion threaded seat 16 correspondingly beveled to the edge 15, so that when the sections 10 and 11 are moved apart or brought together, a screw threaded seating of the head 14 is assured. The sections 10 and 11 are adjusted 15 relative to each other to take up wear on the cylinder or the piston when interfitted with one another, thereby avoiding the re-boring of the cylinder, the latter not being shown in the drawing.

20 The head 14 in its outer face is formed with key sockets 17 so that it can be worked home by a tool in a convenient manner when the piston is within the cylinder, or for the removal of the head 14, while the piston is in place.

25 The rabbeted edge portions 12 and 13 of the sections 10 and 11 overlap one another at all times when these sections are fitted to each other.

30 Formed within the body of the piston A and intersecting the meeting edges of the sections 10 and 11 are wrist pin bosses 18, each being halved concurrent with the edge portions 12 and 13, and such bosses have bolt ears 19 for coupling bolts 20, which are removably fitted therein. In this manner the sections 10 and 11 are adjustably 35 connected together. There is of course to be exteriorly fitted to the skirt of the piston A any conventional type of piston ring, for example as at 21 and 22, respectively.

35 The bosses 18 are formed with beveled threaded openings 23 for adjustably accommodating correspondingly beveled threaded bushings 24, having the wrist pin 25 fitted therein, as is clearly shown in Figures 1 and 4 of the drawing.

40 The bushings 24 are formed with flat faced 45 nut-like inner ends 26 so that the same can be readily and easily adjusted when within the bosses 18, or inserted or removed therefrom.

45 The assembly of the piston A is well disclosed 50 in Figures 2 and 3 of the drawing, while Figure 5 shows the overlap of the edge portions 12 and 13

of the sections 10 and 11 and the association of the head 14 therewith.

What is claimed is:

1. A piston of the kind described, comprising a cylindrical sectional body forming a skirt, rabbeted and saw tooth-like interfitted edge portions on the sections meeting each other, a head removably and adjustably fitting one end of the body when the sections thereof are assembled together, a wrist pin fitted within the body, and means adjustably and detachably connecting the sections of the body together.

2. A piston of the kind described, comprising a cylindrical sectional body forming a skirt, rabbeted and saw tooth-like interfitted edge portions on the sections meeting each other, a head removably and adjustably fitting one end of the body when the sections thereof are assembled

5 together, a wrist pin fitted within the body, means adjustably and detachably connecting the sections of the body together, and bushings associated with the wrist pin and sections of the body.

10 3. A piston of the kind described, comprising a cylindrical sectional body forming a skirt, rabbeted and saw tooth-like interfitted edge portions on the sections meeting each other, a head removably and adjustably fitting one end of the body when the sections thereof are assembled together, a wrist pin fitted within the body, means adjustably and detachably connecting the sections of the body together, and bushings associated with the wrist pin and sections of the body, and adjustably and removably connected to the latter.

RALPH F. WHITE.
